UNITED STATES PATENT OFFICE.

HENRY MAGNESS, OF COLTON, SOUTH DAKOTA.

ATTACHMENT FOR CORN PICKERS.

Application filed February 19, 1925. Serial No. 10,386.

To all whom it may concern:

Be it known that I, HENRY MAGNESS, a citizen of the United States, residing at Colton, in the county of Minnehaha and State 5 of South Dakota, have invented certain new and useful Improvements in Attachments for Corn Pickers, of which the following is a specification, reference being had to the accompanying drawings.

10 This invention relates to an attachment for corn pickers and it is an object of the invention to provide a device of this general character whereby the gathered ears are effectively maintained in desired position with respect to the husking rolls and wherein means are provided for throwing out nubbins at the front of the husking rolls.

15 It is also an object of the invention to provide an attachment of this general character which, when in applied position, is driven from a suitable moving part of the picker to which it is applied.

20 The invention consists in the details of construction and in the combination and arrangement of the several parts of my improved attachment for corn pickers whereby certain important advantages are attained and the device rendered simpler, less 25 expensive and otherwise more convenient and advantageous for use, as will be hereinafter more fully set forth.

The novel features of my invention will hereinafter be definitely claimed.

30 In order that my invention may be the better understood, I will now proceed to describe the same with reference to the accompanying drawings, wherein:—

35 Figure 1 is a view in top plan illustrating an attachment constructed in accordance with an embodiment of my invention in applied position;

40 Figure 2 is a sectional view taken substantially on the line 2—2 of Figure 1 with certain of the parts in elevation;

45 Figure 3 is a sectional view taken substantially on the line 3—3 of Figure 2 with parts in elevation;

50 Figure 4 is a view partly in section and partly in elevation of one of the beater members as herein disclosed;

55 Figure 5 is a view in elevation of one of the bearings for the crank shaft as herein disclosed unapplied.

My improved attachment, as herein disclosed, is particularly adapted for use in

connection with the well known Deering or McCormick corn picker of a type employed in connection with the standing stalks and operates in connection with the husking 60 rolls R upon which the gathered ears are delivered.

The rolls R are of a conventional type and driven in a well known manner and at opposite sides of said rolls R are the side 65 boards 1 of requisite dimensions. Rotatably supported above and slightly to the rear of the rolls R is a fan F embodying four equi-distantly spaced blades 2. The fan F at each of its ends is provided with a trunnion 3 rotatably engaged within a bearing 4 mounted upon the upper edge of a side board 1. To the upper portion of each of the side boards 1 at the forward end thereof is bolted or otherwise secured a block or casting 5 having its forward end portion bifurcated. Snugly engaging within the kerf 6 of said bifurcated end portion is a shank 7 carried by a bearing 8, said bearing being positioned in advance of the 70 side board 1.

The bearings 8 provide mountings for the crank shaft S, said crank shaft being in driven connection through the medium of the gears 9 and 10 with the beater shaft 85 11. The beater shaft has each end portion rotatably supported by a bearing 12 bolted or otherwise secured to the upper portions of the side boards 1. The gear 9 is fixed to the shaft S while the gear 10 is fixed to 90 the shaft 11, said gears 9 and 10 being of desired ratio. The shaft 11 has its opposite end portions in driven connection as by the sprocket chain 14 with a desired driven shaft of the picker proper. 95

Mounted upon the shaft 11 are the beater wheels or discs 15, each of which being positioned above but in relatively close proximity to the bight between adjacent rolls R. The intermediate or central portion of the 100 shaft 11 is angular, preferably square in cross section, and each of the wheels or discs 15 is provided with a similarly formed central opening whereby the wheel or disc 15 when mounted upon the shaft 11 may 105 be keyed for rotation therewith. Each of the discs or wheels 15 is held to the shaft 11 by the brackets 16 bolted both to the wheel or disc 15 and shaft 11.

At predetermined points spaced circumferentially around the wheel or disc 15 are the equi-distantly spaced picker hooks 17 ex-

tending a predetermined distance beyond the periphery of the wheel or disc 15 and to an extent sufficient during a working operation of the rolls R to throw or jerk out nubbins at the front end portion of the rolls R.

The shaft S is provided with a plurality of angularly related cranks 18 with each of which is operatively engaged an end portion of a pitman 19 the opposite end portion of which being secured to an end portion of a propeller blade 20. A propeller blade 20 is positioned directly above each of the rolls R and extends rearwardly and longitudinally thereof to a point in relatively close proximity to the rear end of the roll and the lower marginal portion of the propeller blade 20 is provided therealong with a plurality of longitudinally spaced and forwardly inclined depending fingers 21.

Adjacent its rear end each of the blades 20 has pivotally connected therewith, as at 22, the lower end portion of an upstanding propeller arm 23, said arm extending through the openings 24 provided in the vertically spaced cross members or boards 25. The opposite end portions of the cross members or boards 25, are bolted or otherwise secured to the properly spaced cross bars 26 comprised in the supporting members or braces 27 bolted or otherwise secured to the upper edges of the side boards 1.

Each of the arms 23 at a point between the cross members or boards 25 is provided with a series of longitudinally spaced openings 28 through which is adapted to be selectively disposed a pin 29 herein shown as of a cotter type. This pin 29 serves as a stop or abutment for the lower end portion of an expansible spring 30 surrounding the arm 23 with its upper end portion bearing against a washer 31 mounted upon the arm 23 and in direct contact with the under surface of the upper cross member or board 25. This spring serves to constantly urge the arm 23 and its blade 20 downwardly and the tension of such spring may be regulated or adjusted by changing the position of the pin 29.

The arm 23 above the upper cross member or board 25 is surrounded by a second expansible spring 32 interposed between the washer 33 and a cotter pin or the like 34 selectively disposed through the longitudinally spaced openings 35 provided in the upper portion of the arm 23. The washer 33 surrounds the arm 23 and is in direct contact from above with the upper cross member or board 25. By varying the tension of the upper spring 32 by shifting the position of the pin 34, the tension of the lower spring 30 may be further regulated.

In practice, as the ears are discharged from the picker proper upon the rolls R the oscillation of the blades 20 operate to main-

tain the ears in proper position with respect to the rolls R and assure the same travelling forwardly thereof while the picker hooks 17 operate, as hereinbefore described, to throw out the nubbins which may be wedged between the rolls R at the front or forward end portions thereof and thus prevent the requisite travel or flow of the normal ears. While this is the particular purpose of the hooks 17 yet it is to be understood that they will also operate to throw off the normal ears incident to the travel of said hooks.

From the foregoing description it is thought to be obvious that an attachment for corn pickers constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. In combination with a set of husking rolls, a propeller blade positioned above each of the rolls, yieldable means for supporting each of said blades for oscillatory movement, means for oscillating the blades, vertically disposed discs positioned above and between adjacent rolls, said discs being provided with outstanding picker hooks, and means for rotating the discs.

2. In combination with a set of husking rolls, a propeller blade positioned above each of the rolls, yieldable means for supporting each of said blades for oscillatory movement, means for oscillating the blades, vertically disposed discs positioned above and between adjacent rolls, said discs being provided with outstanding picker hooks, and means for rotating the discs, the means for oscillating the blades being in driven connection with the means for rotating the discs.

3. In combination with a set of husking rolls, a propelling blade positioned above each of the rolls, means for oscillating the blade, a cross member positioned above the rolls, an upstanding arm pivotally connected with each of the blades and freely disposed through the cross member, said arm below the cross member being provided with an abutment, and an expansible spring surrounding the arm and interposed between the abutment and the cross member for urging the arm and blade downwardly.

4. In combination with a set of husking rolls, a propelling blade positioned above each of the rolls, means for oscillating the

- blade, a cross member positioned above the rolls, an upstanding arm pivotally connected with each of the blades and freely disposed through the cross member, said arm below the cross member being provided with an abutment, an expansible spring surrounding the arm and interposed between the abutment and the cross member for urging the arm and blade downwardly, a second abutment carried by the arm above the cross member, and an expansible spring surrounding the upper portion of the arm and interposed between the second abutment and the cross member, said second abutment being adjustable lengthwise of the arm.
- 5 6. In combination with a set of husking rolls, a propelling blade positioned above each of the rolls, means for oscillating the blade, a cross member positioned above the rolls, an upstanding arm pivotally connected with each of the blades and freely disposed through the cross member, said arm below the cross member being provided with an abutment, and an expansible spring surrounding the arm and interposed between the abutment and the cross member for urging the arm and blade downwardly, said abutment being adjustable lengthwise of the arm.
- 10 7. In combination with a set of husking rolls, a propelling blade positioned above each of the rolls, means for oscillating the blade, a cross member positioned above the rolls, an upstanding arm pivotally connected with each of the blades and freely disposed through the cross member, said arm below the cross member being provided with an abutment, an expansible spring surrounding the arm and interposed between the abutment and the cross member for urging the arm and blade downwardly, said abutment being adjustable lengthwise of the arm.
- 15 8. In combination with a set of husking rolls, a propelling blade positioned above each of the rolls, means for oscillating the blade, a cross member positioned above the rolls, an upstanding arm pivotally connected with each of the blades and freely disposed through the cross member, said arm below the cross member being provided with an abutment, and an expansible spring surrounding the arm and interposed between the abutment and the cross member for urging the arm and blade downwardly, said abutment being adjustable lengthwise of the arm.
- 20 9. In combination with a set of husking rolls, a propelling blade positioned above each of the rolls, means for oscillating the blade, a cross member positioned above the rolls, an upstanding arm pivotally connected with each of the blades and freely disposed through the cross member, said arm below the cross member being provided with an abutment, an expansible spring surrounding the arm and interposed between the abutment and the cross member for urging the arm and blade downwardly, said abutment being adjustable lengthwise of the arm.
- 25 10. In combination with a set of husking rolls, a propelling blade positioned above each of the rolls, means for oscillating the blade, a cross member positioned above the rolls, an upstanding arm pivotally connected with each of the blades and freely disposed through the cross member, said arm below the cross member being provided with an abutment, and an expansible spring surrounding the arm and interposed between the abutment and the cross member for urging the arm and blade downwardly, said abutment being adjustable lengthwise of the arm.

In testimony whereof I hereunto affix my signature.

HENRY MAGNESS.
